UNITED STATES PATENT OFFICE.

LESTER P. WINCHENBAUGH, OF HYDE PARK, AND LAWRENCE GENTILE, OF MELROSE, MASSACHUSETTS, ASSIGNEES TO LESTER P. WINCHENBAUGH COMPANY, OF BOSTON, MASSACHUSETTS, A CORPORATION OF MASSACHUSETTS.

PROCESS OF APPLYING COLORING LIQUID TO PAPER.

Application filed August 8, 1919. Serial No. 316,235.

To all whom it may concern:

Be it known that we, LESTER P. WINCHENBAUGH and LAWRENCE GENTILE, citizens of the United States, residing, respectively, at Hyde Park and Melrose, in the counties of Suffolk and Middlesex and State of Massachusetts, have invented certain new and useful Improvements in the Processes of Applying Coloring Liquid to Paper; and we do hereby declare the following to be a full, clear, and exact description of the invention, such as will enable others skilled in the art to which it appertains to make and use the same.

15 This invention relates to a process of applying dye, stain or other coloring liquid to paper or similar material.

The primary object of the invention is to produce a process for use in applying coloring liquid to paper by which novel designs and artistic effects may be produced in an efficient and reliable manner.

With the above object in view the invention consists in a process involving certain novel features hereinafter described and particularly pointed out in the claims.

In the drawing the figure is a view in side elevation of an apparatus which may be employed in carrying out certain steps in the present process.

In the present process a coloring liquid is employed which in practice has been made by dissolving a dye in a liquid solvent. The dye substances which are used should be such that they are completely soluble in the liquid solvent, leaving no sediment. Preferably coal tar or aniline dyes are employed, such dyes having in addition to their ready solubility the property of transparency which enables almost countless variations in color and designs to be produced by the application of the colors in superposed relation at certain points. It has been found particularly advantageous to employ solvents for the dye alcohol, gasoline or similar organic solvents since such solvents produce a rapidly drying solution and cause the coloring liquid to penetrate the paper to a considerable degree, thereby increasing the artistic effect of the design.

After the dye is completely dissolved in the liquid solvent the coloring liquid is introduced into a suitable container from which it may be drawn for transfer to the

paper. To withdraw the coloring liquid 55 from the container in the regulated quantity required for transfer to the paper a section of sheet fabric is introduced into the liquid in the container and is arranged with one end projecting from the liquid. This section of sheet fabric must be made of such material and must be so constructed that the coloring liquid will be drawn from the container through the same by capillary action. Certain kinds of woven wool felt 60 have been found to be well adapted for this purpose.

The coloring liquid may be transferred from the fabric to the paper by placing the paper in contact with the end of the fabric 70 which projects from the color containing receptacle and relatively moving the fabric and the paper so that the fabric is carried along the surface of the paper. The coloring liquid will thus be withdrawn from the 75 receptacle in just the amount required for application to the paper, the liquid being drawn through the fabric to the end thereof which engages the paper as fast as it is applied to the paper. The quantity of liquid 80 withdrawn is regulated by the fabric so there is never any excess of liquid at the point of application to form blots or other imperfections in the designs.

The coloring liquid may be applied to the 85 paper in stripes or streaks by notching the edge of the fabric which engages the paper. Two or more colors may be applied to the paper at the same time by the use of two or more sections of fabric each dipping into 90 a separate receptacle and engaging the surface of the paper at different points. When two or more transparent colors such as are formed by the use of solutions of transparent dyes are applied so that at certain 95 points the colors overlap or are superposed, variations in the resultant colors from the colors applied are produced giving highly artistic effects.

The amount of color discharged upon the 100 paper may be regulated by the use of fabrics of different thicknesses, the greater the thickness of the fabric the more rapid the flow of the liquid therethrough. Also the amount of the liquid deposited on the paper 105 may be varied by varying the rapidity of the relative movement of the fabric and the paper. The greater the speed with which

the paper is passed along the edge of the solution thus withdrawn to a moving sheet of paper. The distribution of the coloring liquid will also vary with variations in the construction of the fabric employed.

Instead of engaging the paper directly with the fabric to transfer the coloring liquid from the fabric to the paper, the fabric may be engaged with a roll or other color receiving device intermediate the fabric and the paper and carried by this device from the fabric to the paper. The figure of the drawing illustrates an apparatus which may be advantageously employed in transferring the liquid from the fabric to the paper in this way. In the illustrated construction the coloring liquid is contained in a receptacle 2 and a section of sheet fabric indicated at 4 is located with one end thereof dipping into the liquid in the receptacle and with the other end thereof resting on a roll indicated at 6 and is held in contact therewith by a weight 8. Below the roll 8 is a cooperating roll 10 between which and the roll 6 the paper is passed, as clearly shown in the drawing. In the operation the rolls are rotated in the directions indicated by the arrows.

30 The surface of the roll 6 is formed with elevations and depressions having any suitable form and arrangement to draw the liquid as required from the fabric, and the fabric 4 thus contacts with and deposits the coloring liquid upon the high points on the surface of the roll. The coloring liquid is then transferred by the roll 6 to the paper as it passes between the rolls in a design corresponding with the design formed on the surface of the roll 6. The roll 10 may have a smooth periphery if desired. In the illustrated construction, however, the surface of the roll 10 is also provided with elevations and depressions corresponding with those on the roll 6 so that the paper is embossed in passing between the rolls.

35 The mechanism above described is illustrated, described and claimed in applicants' copending application Serial No. 316,233, filed on the same date as the present application. In an application Serial No. 316,234, also filed on the same date, applicants have illustrated and described a process related in certain aspects to the present process.

40 Having explained the nature and object of the invention, and having specifically described the manner in which it may be applied, what is claimed is:

1. The process of making colored paper which comprises withdrawing a solution of a dye in alcohol or a similar solvent from a supply in regulated quantity through a capillary sheet fabric and progressively transferring the regulated quantity of the

5 supply in regulated quantity through a sheet of capillary fabric, progressively transferring the solution from the fabric to a moving color receiving device and applying the solution transferred to said receiving device 75 to the paper by passing the paper past said receiving device in contact therewith.

3. The process of making colored paper which comprises withdrawing a solution of a dye in alcohol or a similar solvent from a 30 supply in regulated quantity through a section of capillary sheet fabric, transferring the solution from the fabric as it is withdrawn from the supply to a rotating color receiving roll and applying the solution to 35 the paper by passing the paper along the roll in the direction of movement of the roll and in contact therewith.

4. The process of making colored paper which comprises applying continuously to 90 paper a penetrative solution of a dye in quantity regulated by capillary action and sufficient to cause the same to penetrate the paper and spread from the point of application. 95

5. The process of making ornamental paper which comprises applying a highly penetrative coloring liquid to the paper and embossing the paper while it is wet with the coloring liquid. 100

6. The process of making ornamental paper which comprises embossing paper by passing the same between a pair of embossing rolls and simultaneously applying a highly penetrative coloring liquid to the 105 paper by applying said liquid to one of said rolls and transferring the liquid to the paper during the passage of the paper between the rolls.

7. The process of making ornamental 110 paper which comprises applying a highly penetrative coloring liquid to paper and simultaneously embossing the paper at the point at which the coloring liquid is applied.

8. The process of making colored paper which comprises applying to paper a solution of a dye in a volatile organic solvent of low viscosity in quantity regulated by capillary action and sufficient to cause the same to penetrate the paper and to spread 115 from the point of application. 120

9. The process of making colored paper which comprises applying to paper a solution of an aniline dye in alcohol in quantity regulated by capillary action and sufficient to cause the same to penetrate the paper and to spread 125 from the point of application.

LESTER P. WINCHENBAUGH,
LAWRENCE GENTILE.
